BASEBALL GAME

Application filed December 26, 1928. Serial No. 328,559.

This invention relates to games and has particular reference to a base ball game.

An object of this invention is to provide a game which may be played indoors and which while being amusing will nevertheless require and tend to develop a certain amount of skill in the player.

A further object of this invention is to provide a game of the character described which may be conveniently carried from place to place and which may be economically manufactured on a commercial scale.

Other objects and advantages of this invention as well as the numerous novel details of construction will become more apparent as the following description proceeds, particularly when reference is had to the accompanying drawings wherein,

Figure 1 is a perspective view of a game constructed in accordance with the teachings of this invention;

Figure 2 is a sectional view through one of the elements forming a part of the game shown in Figure 1;

Figure 3 is a plan view of the member shown in Figure 2;

Figure 4 is a plan view of another element forming a part of the game shown in Figure 1;

Figure 5 is a side elevational view partly in section of the device shown in Figure 4;

Figure 6 is a perspective view of one of the playing members shown in Figure 1;

Figure 7 is a vertical sectional view taken through the member shown in Figure 6;

Figure 8 is a perspective view of a portion of the structure shown in Figure 1;

Figure 9 is a perspective view of one of the ball throwing members used in playing the game;

Figure 10 is an elevational view of one of the game pieces in the game;

Figure 11 is a diagrammatic plan view illustrative of the method of playing the game;

Figure 12 is a vertical sectional view through a portion of the structure shown in Figure 1;

Figure 13 is a perspective view of a slightly modified form of construction;

Figure 14 is a sectional view through a portion of the structure shown in Figure 13;

Figure 15 is an elevational view partly in section of a portion of the structure shown in Figure 13;

Figure 16 is a perspective view of a portion of the structure shown in Figure 13, and

Figure 17 is a vertical sectional view through a portion of the modified form of construction.

The present invention contemplates in particular the provision of a game which will give to the player all of the thrills of a real outdoor base ball game. It contemplates the provision of a ball throwing mechanism together with a ball batting mechanism adapted to knock the ball about the game board in the manner of an actual batter in an outdoor base ball game. It contemplates further the provision of members simulating infielders and outfielders capable of functioning similar to the infielders and outfielders in an outdoor base ball game. The invention further contemplates the provision of pockets or the like, in which the playing ball is adapted to be knocked, these pockets representing two and three base hits and home runs. In short, the invention contemplates the provision of a game, in the playing of which substantially

all of the problems presented in a real game of base ball will be encountered and which shall require and develop a certain amount of skill in the player to overcome and solve these problems.

Referring now particularly to the drawings wherein like reference characters designate corresponding parts throughout all views, the numeral 20 designates a game board, which as illustrated, may be substantially circular in shape. The face of the board 20 may be covered with any desired material and is marked to simulate a base ball diamond having the infield 21, outfield 22, base lines 23 and 24 respectively, and the first and third bases 25 and 26 respectively.

The game board further carries a ball throwing mechanism designated generally by the reference character 27, a ball batting mechanism designated generally by the reference character 28 and the members 29 which simu-

late players properly located in the infield and outfield of the diamond.

The game board 20 is preferably surrounded by a wall or fence 30 and may have 5 painted thereon representations of grand stands, pavilions, bleachers and the like, thus giving to the game board the appearance of a complete base ball park. The fence 30 is preferably formed in five sections and these 10 sections are spaced from each other to form the openings 31, 32, 33 and 34 arranged at spaced points around the periphery of the game board 20. The sections of the fence 30 are secured to the game board 20 by suitable 15 angle plates 35, and the sections of the fence 30 are secured to each other by tie bars 36 spanning the openings 31, 32, etc.

From the above, it is believed that the general principles of the game may be clearly 20 understood. A ball 37 is adapted to be directed by the ball throwing mechanism 27 toward the ball batting mechanism 28 and the ball batting mechanism is adapted to bat the ball to knock the same outwardly toward 25 the members 29 and the pockets 31, 32, etc. The members 29 while being normally in an upright position are adapted to be knocked over if struck by the ball 37, the knocking over of one of the members 29 constituting an 30 out for the batter. If, however, the ball avoids all of the members 29, it may find its way to one of the openings 31, 32, etc., in which event, the batter is entitled to a hit of 35 a predetermined number of bases depending upon the opening through which the ball is knocked. For example, the opening 31 might be called a two base hit opening, the openings 32 and 33 three base hit openings, while the opening 34 might be called a home run opening. 40 Thus if the ball is knocked by the batting mechanism through the opening 31, the batter is entitled to a two base hit or if the ball is knocked by the batting mechanism through the openings 32 or 33, the batter is entitled to a three base hit. Obviously also 45 if the ball is knocked through the opening 34, the batter is entitled to a home run. As illustrated in Figure 1 of the drawing, the members 36 may bear indicia indicating the number 50 of bases given by each respective opening.

Referring now particularly to Figures 2 and 3, it will be noted that the ball throwing mechanism 27 includes a base plate 40 which may be fixed to the game board 20 as by the 55 securing members 41. Pivotaly mounted at one end to the base plate 40, as by the pivot pin 42, is a trough shaped member 43 provided at spaced points with the uprights 44 and 45 respectively. The uprights 44 and 45 60 may be U-shaped in cross section and have their sides secured to the sides of the trough shaped member 43. The uprights 44 and 45 are provided with aligned apertures 46 and 47 respectively, to slidably receive a 65 plunger 48.

The plunger 48 is normally urged in the direction of the arrow in Figure 2 of the drawings, by a coil spring 49 sleeved on the plunger 48, one end of this spring abutting against the upright 45 and the other end of this spring abutting against a pin 50, which passes through an opening 51 in the plunger 48. The pin serves not only as an abutment for the spring 49, but serves also to limit the outward movement of the plunger 48 by 70 abutment with the upright 44 as clearly shown in Figure 3 of the drawing.

The plunger 48 is provided at its inner end with a head 52 forming the shoulder 53 for engagement by a catch 54 pivotally mounted on a pin 55 carried by the upright 45. When the plunger 48 is in the retracted position shown in Figure 2 of the drawing, the catch 54 is adapted to engage the shoulder 53 to hold the plunger in its retracted position against the tension of the spring 49. For releasing the catch 54 there is provided a lever 56 having one end secured as at 57 to the catch 54 and having its other end extended through a slot 58 formed in the wall 90 30. Thus by raising up on the end of the lever 56, the catch 54 may be raised to release its engagement with the shoulder 53 to thus permit the plunger 48 to be projected by the spring 49.

As brought out before, the trough 43 is pivoted at its forward end to the base plate 40. This pivotal mounting of the trough 43 permits an adjustment of the trough 43 to vary the angle of travel of the ball 37 from the ball throwing mechanism 27 to the ball batting mechanism 28. For limiting the pivotal movement of the trough 43 about its pivot 42, there is provided a plate 59 fixed to one end of the base plate 40. The plate 105 59 is of less width than the trough 43 and is provided with a tongue 60 offset as at 61 to extend into the trough 43 and between the legs of the upright 45. Thus the trough 43 is limited in its pivotal movement about its pivot 42, by engagement of the edges of the tongue 60 with the legs of the upright 45. In use, the playing ball 37, which may be a soft rubber ball, is placed in the trough 43 in the path of the plunger 48. It has been 110 found that if the ball 37 is spaced a slight distance from the forward end of the plunger 48, the striking of the ball by the plunger will cause the ball to travel at a considerable speed toward the batting mechanism 28. If 115 on the other hand, the ball 37 is placed closely adjacent the forward end of the plunger 48, it has been found that the striking of the ball by the plunger will cause the ball to travel more slowly toward the striking mechanism 28. Thus the ball 37 may be so positioned relative to the end of the plunger 48, as to effect either a rapid or a slow travel 120 of the ball from the throwing mechanism 27 to the batting mechanism 28. To facilitate 125 130

the correct positioning of the ball 37 relative to the end of the plunger 48, there may be provided indicia such as the line 62 traced on the floor of the trough 43 at the point 5 where the ball should be placed to cause the plunger to make the ball travel with considerable speed.

Regardless, however, of whether the ball is positioned for a fast or slow travel, the 10 plunger is retracted to the position shown in Figure 2 of the drawings and the catch 54 is engaged with the shoulder 53. The trough 43 is then angularly adjusted within its limits to vary the angle of travel of the ball 15 and the lever 56 is then raised to release the catch 54, whereupon the spring 49 urges the plunger 48 forwardly causing the same to strike the ball 37 to discharge the ball toward the batting mechanism 28.

20 The ball batting mechanism 28 is shown in Figures 4 and 5 and includes a base plate 70 formed of two superposed plates 71 and 72, these plates being secured to the game board 20, as a unit by the securing members 73. 25 Fixed to the base plate 70 is a pivot pin 74 which may be conveniently secured in upright position by aperturing the plate 72 prior to the securing together of the plates 71 and 72. The pivot pin 74 is provided 30 with a base 75 and is inserted through the opening in the plate 72 from the bottom. The plates 71 and 72 are then welded together adjacent the pivot pin 74 as indicated at 76 in Figure 4 of the drawing. The pin 35 74 is thus fixed firmly in position and is held in this position by the plate 71.

The numeral 77 designates a bat like member pivotally mounted intermediate its ends on the pin 74. To facilitate a free pivoting of the bat 77 about the pin 74, there may be provided a bearing sleeve 78 arranged between the pin 74 and the bat 77.

The bat 77 is constantly urged in the direction of the arrow about its pivot by the 45 spring 79 which is secured at one end to the end 80 of the bat and at its other end to a lug 81 carried by the base plate 70. A lip 82 struck from the upper plate 72 of the base plate 70 limits swinging of the bat 77 about its pivot under the influence of the spring 79.

Pivoted to the base plate 70 as at 83, is a lever 84 having an upturned end 85 adapted to be hooked over the striking end of the bat 77 when the latter is in the position 55 shown in Figure 4 of the drawing. The opposite end of the lever 84 is pivotally connected to a link 86, which extends upwardly and outwardly through a slot 87 in the wall of the game board. The link 86 is provided at 60 its free end with an upturned portion 88, whereby the same may be easily pressed inwardly from a point outside of the wall 30.

In operating the batting mechanism, the bat 77 is swung to the position shown in 65 Figure 4 of the drawing, in which position

the spring 79 is under tension. The end 85 of the lever 84 is then hooked over the striking end of the bat 77 to hold the bat in this position. As the ball 37 approaches the bat from the ball throwing mechanism 27, the 70 link 86 is pushed inwardly to swing the lever 84 about its pivot 83 and to thus release the hook 85 from the striking end of the bat 77. The spring 79 then swings the bat 77 about its pivot 74 to cause the striking end of the 75 bat 77 to strike the ball 37.

In Figures 6 and 7 the members 29 are shown in detail and referring particularly to these figures, it will be noted that each member 29 comprises a thin plate 90 having 80 painted on its forward face the figure of a baseball player. Each plate 90 may be provided with an upwardly extending projection 91 adapted to represent the head of the ball player.

The plates 90 are adapted to be normally positioned in an upright position as shown in Figure 6 of the drawing but the plates are so arranged as to be slightly top heavy in order that they may be easily knocked over when struck by the ball 37. In order to so mount the members 90 on the game board 20 that they may be easily knocked over, there is welded to the rear face of each plate and adjacent the lower edge thereof 95 one plate 92 of a hinge designated generally by the reference character 93. The other hinge plate 94 of the hinge 93 may be secured to the game board 20 as by the securing members 95.

As clearly illustrated in Figure 7 of the drawing, the hinge plate 92 is bent upwardly at a point spaced from the pintle 96 whereby the hinge plate 92 may be more readily folded on the hinge plate 94.

The members 29 are hingedly mounted on the board 20 in the positions normally occupied by players on a baseball team opposing the team at bat and function to score outs when struck by the ball 37 batted by the batting mechanism 28. Members 29 similar to the members 29 are positioned adjacent the foul lines on the baseball diamond to indicate whether a ball is fair or foul when knocked by the batting mechanism.

As brought out before, the openings 31, 32, etc. in the wall 30 are adapted for the passage therethrough of the ball 37 if the ball is knocked in the right direction by the batting mechanism 28 and successfully avoids striking any of the members 29. In order to catch the ball when the same passes through one of the openings 31, 32, etc. there is mounted in each opening a pocket 100. Each pocket is detachably mounted in its respective opening by a frame designated generally by the reference character 101. Referring to Figure 8 of the drawing, it will be noted that each frame includes the base 102 and the sides 103. The frame 101 is 120 125 130

formed of resilient wire bent to form the base and sides aforesaid, and the sides and base are connected by portions of the wire bent backwardly as at 104, then upwardly as at 105, and then forwardly as at 106 to merge into the sides 103. The free ends of the sides 103 terminate in rearwardly extending portions 107 bent laterally to form the extensions 108. The bag is sewed to the 10 base 102 of the frame and to the extensions 108 and in inserting the frame into its respective opening, the sides of the frame are sprung inwardly in order that the sides 103 may be positioned within the opening. The 15 sides are then released whereupon the sides will spring into engagement with the sides of the opening. When the frame is in position in the opening, the base 102 and the extensions 108 will be arranged on the outer 20 side of the wall 30, while the sides 103 of the frame will be arranged on the inner side of the wall 30.

In Figure 9, there is illustrated what might be termed a "sacrifice thrower". This member is designated generally by the reference character 110 and is similar in construction to the throwing mechanism 27, differing from this structure by the elimination of the base plate 40 and by the provision of a slightly different form of catch releasing mechanism.

Referring then particularly to Figure 9, it will be noted that the device 110 includes the trough-shaped member 43' which is somewhat shorter than the trough-shaped member 43. The trough 43' is provided with the uprights 44' and 45' in which is mounted the plunger 48' normally projected by the spring 49' bearing at one end against the pin 50, and at its other end against the upright 45'. The plunger 48' is provided with the head 52' and there is pivotally carried by the upright 45' a catch 54' engageable with the shoulder 53'.

For releasing the catch 54' there is provided, in this form of construction, a lever 111 pivoted intermediate its ends to the upright 45' as at 112. One end of the lever 111 is secured to the upper face of the catch 54' as at 113, while the other end 114 of the lever 111 is flattened to form a finger piece whereby this end of the lever may be readily depressed. Obviously, downward pressure on the end 114 of the lever raises the catch 54' to release the plunger 48'.

In Figure 10 there is illustrated one of the game pieces which may comprise a lead casting 115 shaped to simulate the figure of a ball player. There are provided a number of 60 these figures and they are adapted to be placed about the game ball in a manner hereinafter to be more fully described.

Referring now particularly to Figure 11 of the drawing wherein the game board is 65 semi-diagrammatically shown, the playing of

the game will be described somewhat in detail. Before starting the game, the fielders 29 together with the foul markers 29' are set in an upright position. The two foul markers 29' are merely to determine whether a 70 batted ball rolling along the first or third base line is fair or foul. If the ball strikes the foul marker or rolls outside of the marker, it is a foul ball. After having been knocked down, a fielder or foul marker should be set 75 up again before the next turn at bat.

With all of the fielders and foul markers in upright position, the player representing the team at bat takes his position at the batting mechanism 28, while the player representing the team opposing the team at bat takes his position adjacent the pitching mechanism 27. The latter then places a ball in the trough 43, taking care to so locate the ball as to cause a fast or slow discharge of the same depending upon the speed desired, then adjusts the trough 43 about its pivot to give the desired angle to the travel of the ball from the pitching mechanism to the batting mechanism. The player representing the pitcher then actuates the lever 56 to release the catch 54 whereupon the ball 37 is discharged toward the batting mechanism. At the proper moment the batter releases the bat 77 by properly actuating the link 86, whereupon the bat 77 is swung about its pivot by the spring 79 and caused to strike the ball 37. It will be found that the ball 37 will be 85 knocked by the bat 77 outwardly toward the members 29 and openings 31, 32, etc.

If the batter scores a hit, one of the figures 115 is placed on the base and in placing the player on the bases, these players should be placed directly in front of the baseman upon whose base they are positioned. For example, a runner on first base should be placed directly in front of the first baseman, a runner on second base directly in front of the shortstop, and a runner on third base directly in front of the third baseman. By so placing the base runners, the batter's chances for making a safe hit will not be jeopardized but will leave a clear field in which to hit a ball.

In playing the game, the following main rules should be observed. The batter and pitcher should both have their hands and arms entirely outside of the playing field when operating their respective mechanisms. Any infraction of these rules draws a penalty which may consist of a balk for the 115 pitcher or a strike for the batter.

A batted fair ball is safe and scores as a base hit if it passes cleanly between the fielders or if it rolls beyond and clear of the base line between first and second bases, or the line between second and third bases without touching either the pitcher or a fielder. If a batted fair ball passes through the playing field and passes out of the field through one of the openings 31, 32, etc., it entitles the 120 125 130

batter to as many bases as the sign indicates over the opening through which the ball passes. If a batted fair fly ball clears the fence it entitles the batter to a home run.

5 On one base hit batter and base runners advance one base each. On one base hit if the ball passes between the pitcher and center fielder without touching either one and strikes the fence, a base runner on second base scores (naturally a base runner on third scores also), but a runner on first base advances to second base only. On two base hit batter and base runners advance two bases each. On three base hit batter advances 15 three bases and all base runners score. On home run batter and all base runners score. On base on error batter and base runners advance one base each. On base on balls batter goes to first base but base runners do not advance unless forced to do so.

20 A base on error may be obtained as follows: If a batted fair ball strikes an infielder, does not knock the infielder down, and rolls behind the infielder without knocking another fielder down, the batter is entitled to his base on an error. If a batted fair ball strikes an outfielder, does not knock the outfielder down, and rolls away from the outfielder in any direction without knocking another fielder down, the batter is entitled to his base on an error. If a batted fair ball strikes the pitcher, or a fielder without knocking the fielder down, and by so doing is deflected through an exit in the fence, the batter is entitled to two bases on the error and all base runners advance two bases each. If a batted fair ball strikes the pitcher, or a fielder without knocking the fielder down, and by so doing bounds over the fence, the batter is entitled to two bases on the error and all base runners advance two bases each. If a batted fair ball strikes the pitcher, or a fielder without knocking the fielder down, and glances off and strikes a base runner without knocking any other fielder down, the batter is entitled to his base on an error. If, in so striking the base runner, the ball is deflected through an exit in the fence or if the ball bounds over the fence, the batter is entitled to two bases on the error and all base runners advance two bases each.

25 If a batted fair ball rolls through the playing field and is stopped or interfered with in any manner before it stops rolling, by any player on the team opposing the batter, the batter shall be given his base on a base hit. If, in the opinion of the umpire, the ball thus interfered with was rolling toward an

exit in the fence and would otherwise have passed through the exit, the umpire shall allow the batter as many bases as the sign indicates over the exit toward which the ball was rolling. All base runners shall advance 70 accordingly.

25 By utilizing the device 110 shown in Figure 9 it is possible to determine whether or not a runner on third base should score after an out. This may be determined as follows: 75 The base runner is placed on the base line between third base and home plate, distant from the plate his own length and facing the plate. This position is indicated as X in Figure 11. The device 110 for throwing the ball from the outfield is then loaded with the ball and placed alongside of and slightly to the rear of the outfielder making the put-out. For example, if the right fielder makes the putout, the device is placed as indicated 80 in Y in Figure 11 of the drawing. The spring is then released and the ball ejected toward the base runner attempting to score; if the ball thus thrown from the outfield touches the base runner he is out, otherwise he scores 85 a run. Any other base runners advance one base each on the play, no matter what the outcome of the play is, unless the runner attempting to score being put out, the play constitutes the third out for the inning.

90 To determine whether or not a batter is out, the following rules are followed: If a batted fair ball strikes a fielder before it hits the fence, and knocks the fielder down, the batter is out. If in thus striking the fielder the ball hits with sufficient force to knock the fielder down and cause him to spring back into position again, the batter is out. If a batted fair ball is stopped by a fielder without knocking the fielder down and the ball does not roll away from the fielder, the batter is out. If a batted fair ball strikes an infielder, does not knock the infielder down, and rolls away from the infielder to either side of him but not behind him, or if the ball rolls back toward or into the diamond, the batter is out. If a batted fair ball is stopped by the pitcher, the batter is out. If a batted fair ball strikes the pitcher and rolls back toward or over the plate, or toward or over the base line between home plate and first base or the line between home plate and third base, the batter is out. If a batted fair ball strikes the pitcher and rolls toward the base line between first and second bases or the line between second and third bases without rolling over and clear of said base line, the batter is out. If a batted fair ball strikes a fielder, does not knock the fielder down, but bounds off and knocks another fielder down before the ball hits the fence, the batter is out. If a batted fair ball strikes a base runner and also knocks a fielder down, the batter is out. If a batted foul ball strikes the fence but once, and bounds out into the playing field and 100 105 110 115 120 125 130

knocks down either the first baseman or the third baseman, the batter is out; the ball however must have struck no other object between the fence and the first or third baseman.

If a batted fair ball strikes a base runner before it strikes any other object, and does not knock a fielder down, the base runner so struck is out; the batter is safe at first and is given credit for a base hit; other base runners do not advance unless forced to do so. If, upon striking the base runner, the ball also knocks two fielders down before it hits the fence, then the double play rule applies.

A double play may be scored if a batted fair ball strikes a fielder, bounds off and strikes another fielder before the ball hits the fence and knocks both fielders down. In this case the batter and the base runner nearest home plate are out, while other base runners advance one base each on the play unless it constitutes the third out for the inning. The same rule applies if a batted fair ball strikes the pitcher, bounds off and knocks down a fielder before the ball hits the fence. If the ball knocks down three fielders before it hits the fence, the play should be scored as a triple play.

Strikes and balls may be counted as follows: As there are no fielders inside of the base lines, in the infield, if a batted fair ball does not strike the pitcher and does not roll beyond and clear of the base line between first and second bases or the line between second and third bases, it shall be called a foul strike. If the batter strikes at a pitched ball before the ball reaches the plate, and the ball strikes the bat after the bat has come to rest from its swing, it shall be declared a strike and not a foul strike; if the play constitutes the third strike, the batter shall be declared out on strikes. If a pitched ball curves away from the plate and strikes the bat while the bat is in batting position, and the batter does not strike at the ball, it shall be called a ball and not a foul strike. When there are two strikes on the batter if a foul tip glances off the bat and is caught in the catching pocket (the space behind the opening in the fence to the rear of the home plate), the batter shall be declared out on strikes.

If a pitched ball, after leaving the pitching runway, does not roll as far as the home plate, it shall be called a ball, providing of course the batter does not strike at it. If, upon being pitched, the ball does not leave the pitching runway, or if the plunger of the apparatus does not strike the ball, it shall be called a ball, whether or not the batter strikes at it. A pitched ball that passes wide of the plate naturally is a ball if the batter does not strike at it.

For indicating the various scores the structure shown in Figure 12 may be provided. By reference to this figure together with Figure 1, it will be noted that one section of

the fence, for example the section designated as 30' may be provided on its inner face with the channels 125. These channels 125 may be formed of elongated metal strips having their longitudinal edges return bent as at 126 and may be secured in place by the struck out ears 127 adapted to pass through openings in the wall 30 and to be bent laterally as clearly illustrated in Figure 12 of the drawing. Stencilled on the wall above the channels, may be indicia dividing the channels into columns, there being one column for the teams and one column for each of the innings of the game. Suitable cards bearing the names of the teams and the runs per inning may be inserted in the channels 125 to accurately indicate the scores of the teams by innings.

For indicating the strikes, balls and outs for each inning there may be provided a box like member 130 secured to the upper edge of the section 30' as by the angle plate 131. This box like member may have the openings 132 in its forward face and back of each opening there may be mounted a cylinder indicating member such as 133 carrying thereon indicia representing the number of outs, strikes or balls. It will be obvious that one member 133 will be provided for each item to be indicated, that is, one for balls, one for strikes and one for outs. Each member 133 may be rotated by the shaft 134 passing upwardly through a bracket 135 arranged above the box 130. The bracket 135 forms a housing open at its rear end and there may be mounted on each shaft 134 an indicating member 136 whereby the position of the member 133 may be observed from the rear of the box 130.

By properly utilizing the scoring mechanism above described an accurate check may be kept on the scores of the teams, thus still more closely simulating the playing of a real outdoor ball game.

In Figure 13 a slightly modified form of construction is shown which while similar in general principles to the structure above disclosed, varies in certain details. In this form of construction the game board 20' is similar to that above described as are the location of the openings 31', 32', etc. The pockets 100' instead of being secured in the openings in the manner brought out above, may be nailed as at 150 to a frame 151 surrounding each opening.

The pitching mechanism 27' may be modified and as illustrated in Figure 14 may comprise a trough-shaped member 151 pivoted to the game board 20' as by the pivot pin 152. The movement of the trough 151 about its pivot may be limited by means of a pin 153 secured to the board 20' and passing through a slot 154 in the trough 151. The trough may be provided with uprights 155 and 156 provided with openings for slidably receiving a

plunger 157. The plunger 157 may be urged to its projected position by a spring 158 bearing at one end against the upright 156 and bearing at its other end against an abutment 159 carried by the plunger 157.

The plunger 157 is provided with a head 160 forming a shoulder 161 adapted to be engaged by a catch 162 secured to the end of a lever 163 pivotally mounted on a pin 164 carried by the ears 165 projecting upwardly from the trough 151 adjacent the upright 156. The opposite end of the lever 163 may project through a slot 166 formed in the upright 155 and may be normally urged upwardly by a spring 167 sleeved on a pin 168 which pin passes through an opening 169 formed in the lever 163, the pin being secured at its upper end to the upright 155 as at 170. The spring 167 normally urges one end of the lever 163 upwardly, thus tending to maintain the catch 162 in engagement with the shoulder 161. For depressing the end of the lever 163 to release the catch 162 there may be provided a cord 171 passing over a roller 172 and out through the wall of the game board as illustrated at 174. Obviously a pull on the cord 171 depresses the one end of lever 163 to release the catch 162 whereby the plunger 157 is projected by the spring 158 to impart movement to the ball 37'.

The batting mechanism may also be slightly modified and may include a bat 180 pivoted on a pin 181 carried by the plate 182 secured to the game board 20'. A spring 183 secured at one end to the bat 180 and at its other end to the wall 30' of the game board tends to swing the bat about its pivot while a catch 184 is so positioned as to be hooked over the striking end of the bat to hold the same in the position shown in Figure 13 of the drawing. The hook 184 may be formed on the end of a rod 185, this rod being pivoted intermediate its ends to a rod 186 secured as at 187 to the wall 30'. The free end of the rod 187 may be bent downwardly and provided with a buffer 188 for limiting swinging of the bat 180 by the spring 183.

The rod 185 is adapted to be swung about its pivot by an arm 190 which is pivotally secured at 191 to the outer end of the rod 185, the rod 190 passing through the wall 30' of the game board as clearly illustrated in Figure 15 of the drawing. Obviously with the parts in the position shown in Figure 13 of the drawing, as the arm 190 is pushed inwardly the rod 185 will be moved about its pivot to swing the catch 184 free of the end of the bat 180 whereby the bat will be swung about its pivot by the spring 183.

A further feature of the modified construction is in the structure of the fielders 29'. Each fielder may comprise a flat plate 200 having a forwardly bent portion 201 adjacent its lower edge. Each plate may further be provided with the rearwardly bent ears

202 apertured as at 203 to receive the staple 204 fixed to the game board 20'. The staple 204 forms a pintle about which the ears 202 pivot. The plates 200 are adapted to be marked on their faces to represent ball players and are adapted to be normally positioned upright while being capable of being knocked over by the ball 37' in the manner brought out with reference to the fielders 29.

A further feature of the modified construction is the provision of separate grand stands adapted for detachable connection with the wall 30'. These grand stands may be formed as box like members 205 simulating miniature pavilions. For detachably connecting these members to the wall 30' there may be provided eyes 206 carried by the wall 30' and adapted to receive hooks 207 carried by the stands 205. The provision of separate stands in this manner lends considerably to the appearance of the game board and causes the same to still more closely simulate a regular base ball park.

The playing of the game on the modified construction is similar to the playing of the game as above described, and it is therefore believed that the structure and operation of the modified form will be readily apparent.

While the invention has been described with considerable detail it is to be clearly understood that the description is for the purposes of illustration only, and is not definitive of the limits of the inventive idea. The right is therefore reserved to make such changes in the details of construction and arrangement of parts as will fall within the purview of the attached claims.

What I claim as my invention is:

1. A game including in combination, a game board, a plurality of members hingedly mounted on said game board, a ball striking mechanism, a ball throwing mechanism for directing a ball toward said ball striking mechanism, and means for actuating the said ball striking mechanism to cause the same to knock said ball toward said hingedly mounted members.

2. A game including in combination, a game board simulating a base ball diamond, pockets arranged at spaced points about the periphery of said game board, members simulating base ball players hingedly mounted at spaced points on said game board, a ball striking mechanism, a ball throwing mechanism for directing a ball toward said ball striking mechanism, and means for actuating said ball striking mechanism to cause the same to knock the ball toward said hingedly mounted members and said pockets.

3. A game including in combination, a game board, a ball throwing mechanism, a ball striking mechanism, and members hinged at spaced points to said game board, said members being adapted to be vertically positioned and being adapted to be knocked to horizon-

tal positions when hit by a ball struck by said ball striking mechanism.

4. In a game, a ball batting mechanism including in combination, a base plate, a pivot pin carried by said plate, a bat pivoted on said pin, a spring secured to one end of said bat for moving the same about its pivot, a lever pivoted on said base plate, said lever having an angularly bent end adapted to engage the free end of said bat to hold the same against movement by said spring, and means for moving said lever to release the said bat, whereby said bat may be moved about its pivot by the said spring.

5. In a game, a game board simulating a base ball diamond, members simulating base ball players hinged to said game board, figures simulating base ball players adapted for positioning on said game board, and a ball throwing mechanism adapted for positioning adjacent any one of said members for directing a ball toward one of said figures.

6. In a game, a game board, a wall surrounding said game board, said wall having an opening, a pocket, and means for detachably mounting said pocket in said opening, said means including a three sided resilient frame carrying said pocket, the sides of said frame being adapted for yieldable engagement with the sides of said opening.

7. A game including in combination, a game board, a ball throwing mechanism, a ball striking mechanism, members adapted to be vertically positioned on said game board and adapted to be knocked over to horizontal positions when hit by a ball struck by said ball striking mechanism, each of said members being provided with rearwardly extending ears, and a rod fixed to said game board adjacent each of said members, each rod being provided with a horizontally arranged portion extended through the ears of its respective members to constitute a horizontal hinge pintle therefor.

45 In testimony whereof I affix my signature.
JOHN B. SECHLER.
